UNITED STATES PATENT OFFICE.

MADISON LEE KIRKMAN AND FREDRICK S. WIER, OF RICHMOND, INDIANA; SAID
WIER ASSIGNOR TO SAID KIRKMAN.

LUBRICATING SYSTEM.

1,354,663.

Specification of Letters Patent.

Patented Oct. 5, 1920.

Application filed July 21, 1919. Serial No. 312,221.

To all whom it may concern:

Be it known that we, MADISON LEE KIRKMAN and FREDRICK S. WIER, both citizens of the United States, residing in the city 5 of Richmond, in the county of Wayne and State of Indiana, have invented a new and useful Lubricating System, of which the following is a full, clear, and comprehensive specification and exposition, the same being 10 such as will enable others to construct and apply the same with exactitude.

Our present invention relates to a system of lubricating motors, engines, air compressors, and other analogous mechanisms, by 15 means of a self maintained spray or atomization whereby the various parts to be lubricated are contained in or communicate with an inclosure in which a cloud or fog of atomized lubricant is constantly maintained throughout the inclosure when the parts to be oiled are in operation accomplishing their usual functions.

The object, therefore, of this invention, broadly stated, is to provide an oiling or 25 lubricating system of the nature stated, which will be simple in character, positive in action, automatic in operation, requiring but a minimum of attention and providing a maximum of efficiency, involving no moving parts in its construction and installation, and in which the production and installation thereof will be practically *nil*.

Other minor objects and particular advantages of the invention will be brought 30 out and made apparent to the ordinary mechanician in the course of the following description, and that which is new will be correlated in the appended claims.

One manner of carrying out the principles 40 of our invention in a practical manner is shown in the accompanying two-sheets of drawings, in which—

Figure 1 is a longitudinal section, taken centrally through a single cylinder engine 45 and showing our invention as applied thereto in operative position. Fig. 2 is a cross section of the same, as taken through the crank-shaft of the engine shown in Fig. 1. Fig. 3 is a central vertical section of the 50 check-valve. Fig. 4 is an outside elevation of the check-valve alone. Fig. 5 is an outside elevation of the atomizer alone. And

Fig. 6 is a longitudinal vertical central section of the atomizer alone.

Similar indices denote like parts throughout the several views.

It is to be understood, however, that our invention is not to be limited to a single cylinder or to a stationary engine, as it is 60 equally applicable to various types of engines and compressors.

In order that the construction, the principles, and the advantages of our invention may be more fully understood and appreciated, we will now take up a detail description thereof, in which we will set forth the construction and the operation as fully and comprehensively as we may.

In the drawings we have shown our invention as applied to a single cylinder internal combustion engine, in which letter A denotes the cylinder, in which is reciprocately mounted the piston B, which carries the crank-pin E. Letter C denotes the crank-shaft, which is connected with the 75 crank-pin E, and therefore with the piston B, by means of the connecting rod D in the usual manner.

Letter F denotes the crank-case in which the shaft C and the connecting-arm D operate. Letter G denotes a plug which closes the aperture usually employed for a breather or vent. Letter H denotes the handhole-closure, by which access may be had to the interior of the crank-case F. The chamber 80 formed by the walls of the crank-case is denoted by the letter I, and this chamber merges into the interior of the cylinder A. The chamber I is formed circular, in longitudinal section as shown in Fig. 1, whereby 85 its lower wall slopes from the right and the left to a common center.

The above parts are shown and described only to make clear the invention herein-after set forth, and it is to be understood 90 that our invention is not to be limited to said parts as shown, as our invention may be employed with a plurality of cylinders in connection with a single crank-shaft, and it may be employed with various types of 95 engines and compressors.

Referring now to the invention proper: Numeral 1 denotes the lower wall or bottom of the oil cellar, the upper wall of said cel-

lar being formed by the bottom wall of the crank-case F which is in the nature of a partition. The bottom of the crank-case and the bottom of the oil-cellular being, in this 5 instance, integrally connected by the side walls 2 and 3 of the oil cellar. Numeral 4 denotes a plug for closing the cleanout aperture of the oil cellar. And numeral 5 denotes a plug closing the filler aperture of 10 the oil cellar. By reason of the location of the filler aperture it is apparent that the oil cellar can be loaded only to a predetermined height which, manifestly, will never be higher than the lowest part of the 15 crank case, thereby always maintaining an air-chamber or air-space 6 above the oil 7 which is contained in the oil cellar.

In the lowermost point of the bottom of the crank case there is removably inserted 20 a check-valve for permitting condensed and unused oil which accumulates in the crank-case to flow back into the oil cellar. Said check-valve comprises a body 8, having an offset shell 9 integral therewith. An 25 aperture 10 extends from the lower end upward into the body 8, and it terminates in the cross-over passageway 11, which latter leads into the chamber 12 formed in the shell 9. The lower portion of the chamber 30 12 is slightly contracted to form a spherical valve seat for the ball 13 which is contained in the chamber 12 and normally rests by gravity on said valve seat. Access to the interior of the chamber 12 is obtained 35 through an aperture in the upper end of the shell 9, which aperture is closed by the plug 14. Numeral 15 denotes the passage-way leading from the lowest part of the chamber 1 and extending upward through the 40 valve seat into the chamber 12.

From the above it is apparent that provision is made for the oil to pass from the chamber 1 upward through the passage 15, then upward around the ball 13, then into 45 the chamber 12, and then through the cross-over 11 into the aperture 10, and finally downward, through the channel 10, into the oil cellar, but it is apparent that passage in the opposite direction, that is from the oil cellar into the crank case, is prevented 50 by the valve, that is by the ball 13 resting on its seat.

The atomizer or sprayer is the most essential single feature of our invention, and 55 it comprises the head 16 whose lower portion, or stem, is threaded into an aperture therefor formed through said partition which forms the bottom of the crank-case, that is through that portion of the crank- 60 case which divides the chamber 1 from the oil cellar, and in a part thereof which is at a higher elevation than that of the check valve. The head 16 has a channel 17 extending vertically through the stem portion 65 only, and which connects at its upper end

with the aperture 18, the latter extends out horizontally through the wall of the head and it is always located above the bottom of the crank-case, as is shown in Figs. 1 and 5.

A tube 19 has its upper end portion secured in the stem of the head 16 whereby the channel in the tube 19 forms a continuation of the channel 17 of the head. Located slightly below the stem of the head 16 an air aperture 20 is formed through the wall of the tube 19. The lower end of the tube 19 is formed beveled, as indicated at 21, whereby it will be impossible to close the lower end of the opening in the tube 20 even though the tube come into contact with the bottom 1 of the oil cellar.

The operation of our invention is substantially as follows: A supply of oil 7 is placed in the oil cellar through the opening closed 35 by the plug 5, by which it will be impossible to overload the oil cellar and will always maintain an air chamber 6 above the oil. Now if the engine be operated in the usual manner it is apparent that as the piston B 90 moves away from the crank-shaft it will tend to form a partial vacuum in the crank-case F, and as the only inlet to the crank case, for air or oil, is through the atomizer it is therefore evident that the oil 7 will be 95 drawn up through the tube 19, and at the same time air will be drawn into the tube 19 through the aperture 20, and therefore the combined oil and air will issue into the 100 crank-case from the opening 18 in the form of fine fog or spray, and the air in the crank-case will soon become highly charged with very fine particles of oil in suspension, and the movements of the arm D will tend to 105 circulate and distribute the fog of oil in such manner that the walls of the cylinder, as well as the bearings, will be properly lubricated, and that without danger of over or under lubrication as in the case of other 110 oiling systems.

It is apparent that the surplus oil which accumulates or condenses on the walls of the crank-case or other parts will gravitate to the check-valve, through which it will be conducted back to the oil cellar to be again 115 used as before.

From the above it will be apparent that we provide a highly efficient oiling system in which it is impossible to over lubricate, thereby dispensing with the danger of oil 120 passing around the piston to form soot or carbon in the combustion chamber, and also economizing in the use of oil and cost of maintenance.

Having now fully shown and described 125 our invention, what we claim and desire to secure by Letters Patent of the United States, is—

1. In combination with an inclosed crank case, an oil cellar located below the crank 130

case, a check valve located in the bottom of the crank case and adapted to drain the crank case into the oil cellar but preventing passage from the oil cellar into the crank case, an atomizer head located in the bottom of the crank case, and a tube extending from the atomizer head to near the bottom of the oil cellar, there being an oil inlet and an air inlet in said tube both of which are within 10 the oil cellar and there being an exit from said tube through the head into the crank case.

2. In combination with a crank case having a cylinder communicating therewith and a piston operative in the cylinder, an oil cellar adjoining the crank case and constructed to provide an air chamber in the oil cellar and above the maximum height of the oil in the oil cellar, an atomizer adapted 20 to convey oil and air from the oil cellar and operated by partial vacuum in the cylinder due to the movement of the piston with the atomized aerated oil adapted to fill the crank case and the adjoining portion of the cylinder, and means for permitting the condensed oil to return to the oil cellar through a valve preventing passage from the oil cellar into the crank case.

3. In combination with a crank case having a cylinder communicating therewith and a piston operative in the cylinder, an oil cellar adjoining the crank case and constructed to at all times provide an air space above the oil in the oil cellar, a check valve

permitting oil and air to pass from the crank 35 case into the oil cellar and an atomizer adapted to draw oil and air from the oil cellar and deliver them as atomized oil or fog into the crank case.

4. In combination with a crank case having a cylinder communicating therewith with a piston operative in the cylinder, an oil cellar located below the crank case, a partition dividing the crank case from the cellar, means for preventing the oil in the 45 cellar from rising beyond a certain level below said partition whereby an air space is always maintained below the partition and above the oil in the cellar, a check valve secured in an aperture in the partition and adapted to constantly drain the crank case into the cellar and also preventing passage 50 of air or oil from the cellar into the crank case, and an atomizer secured in said partition and projecting thereabove and extending into the oil in the cellar and having an air inlet opening thereinto from the air space in the cellar, all substantially as set forth.

In testimony whereof we have hereunto 60 subscribed our names to this specification in the presence of two subscribing witnesses.

MADISON LEE KIRKMAN.
FREDRICK S. WIER.
